Patented May 2, 1916.

INVENTOR
HARRY ULMER
BY HIS ATTORNEY
Harry Smith

UNITED STATES PATENT OFFICE.

HARRY ULMER, OF PHILADELPHIA, PENNSYLVANIA, ASSIGNOR TO HARDWICK & MAGEE COMPANY, OF PHILADELPHIA, PENNSYLVANIA, A CORPORATION OF PENNSYLVANIA.

DESIGN FOR WOVEN FABRIC.

48,998.

Specification for Design.

Patented May 2, 1916.

Application filed March 8, 1916. Serial No. 82,939. Term of patent 3½ years.

To all whom it may concern:

Be it known that I, HARRY ULMER, a citizen of the United States, residing in Philadelphia, Pennsylvania, have invented a new, original, and ornamental Design for Woven Fabric, of which the following is a specification.

In the accompanying drawing I have shown sufficient of the body and border of a piece of woven fabric to illustrate my design.

I claim:

The ornamental design for woven fabric as shown.

HARRY ULMER.

Witnesses:

H. J. SELTZER,

Wm. M. BRINKWORTH.
